UNITED STATES PATENT OFFICE.

GEORGE A. GILLEN, OF JERSEY CITY, NEW JERSEY, ASSIGNOR TO GILLEN LABORATORIES CORPORATION, OF ELMHURST, LONG ISLAND, NEW YORK, A CORPORATION OF DELAWARE.

SOUND-REPRODUCER MOUNTING.

Application filed September 18, 1926. Serial No. 136,938.

This invention relates to improvements in sound reproducer mountings and has for its object to provide a device having a rotary stylus for engagement with the record disc 5 of the usual phonograph.

Another object of the invention is to provide a device which may be removably secured to the stylus arm of the usual reproducer without in any way altering its construction.

As a further object the invention is the provision of means for varying the volume of tone reproduced to meet varying requirements.

With the above and other objects in view the invention consists in the novel construction, combination and arrangement of parts which will be fully set forth in the following specification, claimed and illustrated in 20 the accompanying drawing, in which,

Figure 1, is a side view on a greatly enlarged scale of this improved stylus and the mounting therefor, portions being broken away to more clearly illustrate the details 25 of construction,

Figure 2, is a view taken at right angles to Figure 1,

Figure 3, is a horizontal sectional view taken on line 3—3 of Figure 1, and, 30 Figure 4, is a plan view of a modified form of the clamp.

Referring to the drawings, the numeral 10, designates a stylus arm provided with the customary set screw 11, by means of which 35 the stylus is removably held in the socket 12. This improved stylus comprises a shank 13, having formed at one end a pair of divergent arms 14. Formed adjacent the extreme ends of the arms and in their inner faces, are recesses 15, for the reception of jewels 16, forming the bearings for the rotary stylus which will be more fully hereinafter described. Formed in the outer sides of the arms intermediate the jewel recesses and their 45 convergent ends, are recesses 17, for a purpose to be more fully hereinafter set forth.

Mounted on a shaft 18, the ends of which taper as at 19 to fit in recesses formed in the jewels 16, is a disc 20 which is ground to a fine edge 21 for contact with the walls of the record groove. It will thus be seen that the disc is mounted to rotate between the arms, and owing to the jewel mounting of the

shaft 18, lost motion between the moving elements is eliminated.

In order that the tones may be varied so that the volume of reproduction is changeable to meet varying tastes, a yoke 22, comprising a pair of side bars 23 connected at opposite ends by end members 24 and 25 is provided. As shown in the drawings, the end member 24 is formed with an inwardly projecting boss 26 for engagement in one of the recesses 17, while the opposite end member 25, is formed with an internally 65 screw threaded opening for the reception of the pointed set screw 27 which engages in the recess 17 opposite that into which the boss 26 is fitted. It is to be understood that if so desired, one of the side bars 23 may be eliminated as shown in Figure 4, without departing from the spirit and scope of the invention, and that its operation is essentially the same as that of the yoke shown in Figure 3.

In use, when it is desired that the volume be increased, the yoke 22 is placed in the position shown in Figures 1 and 2, and owing to the reduction of length between the stylus and the clamp, the resiliency of the arms 80 will be decreased and the full vibration of the diaphragm (not shown) effected, thus obtaining full volume. Upon moving the yoke toward the convergent ends of the arms, their resiliency is increased, thus producing a damping effect upon the stylus arm through the absorption of some of the mechanical energy of the stylus, and reducing the volume of tone reproduced. It is thus clearly apparent that a wide range of volume 85 control may be had without changing the stylus or stylus arm.

What is claimed is:

1. In a sound reproducer, a stylus arm, a rotary stylus, and means for varying the resiliency of the rotary stylus with relation to the stylus arm of the reproducer whereby the volume of tone reproduced may be varied.

2. In a stylus for sound reproducing machines, a rotary element for engaging a record tablet, means for supporting the rotary element at the end of the stylus arm of a reproducer, and means intermediate the ends 100 of the stylus supporting element for increasing or decreasing the resiliency between the 105

rotary element and the stylus supporting element.

3. The combination with a stylus for sound reproduction, and a forked member connecting the stylus with the stylus arm of a reproducer, of means for varying the resiliency of the forked member, whereby the volume of the tones reproduced may be varied.

4. The combination with a stylus for sound reproduction, and a forked member supporting the stylus and connecting the same with the stylus arm of a reproducer, of a yoke adjustably mounted on the forked member for varying its resiliency, whereby the tones reproduced may be soft or loud.

5. As a new article of manufacture, a stylus for sound reproduction comprising a shank adapted to fit the stylus arm of a sound reproducer, a forked member at one end of the shank, a rotary stylus mounted between the tines of the forked member, and means for varying the resiliency of the tines of the fork, whereby the tones reproduced may be loud or soft.

6. As a new article of manufacture, a

stylus for sound reproduction comprising a shank adapted to fit the stylus arm of a sound reproducer, divergent arms at one end of the shank, a rotary stylus mounted between the arms, said arms being provided on their outer sides with recesses, and a yoke adapted to engage the arms and to be held in place by engagement with the walls of the recesses to vary the resiliency of the arms, whereby the tones reproduced may be made soft or loud.

7. As a new article of manufacture, a stylus for sound reproduction comprising a shank adapted to fit the stylus arm of a sound reproducer, divergent arms formed at one end of the shank, a shaft rotatable adjacent the free ends of the arms, a stylus disc mounted on the shaft, the arms being provided at spaced intervals with horizontally aligned recesses, a yoke, a boss carried by the yoke and adapted to enter certain of the recesses, and a screw carried by the yoke for entrance into the recess opposite the boss.

Signed at New York, N. Y. this 15th day of September, 1926.

GEORGE A. GILLEN.
